UNITED STATES PATENT OFFICE.

GEORGE C. RAHN, OF ERIE, PENNSYLVANIA.

METAL-MELTING FURNACE.

1,333,629.

Specification of Letters Patent. Patented Mar. 16, 1920.

Application filed December 19, 1918. Serial No. 267,433.

To all whom it may concern:

Be it known that I, GEORGE C. RAHN, a citizen of the United States, residing at Erie, in the county of Erie and State of Pennsylvania, have invented new and useful Improvements in Metal-Melting Furnaces, of which the following is a specification.

This invention relates to metal melting furnaces and consists in certain improvements in the construction thereof as will be hereinafter fully described and pointed out in the claims.

The invention is illustrated in the accompanying drawings as follows:—

Figure 1 shows a side elevation of the furnace, partly in section.

Fig. 2 a section on the line 2—2 in Fig. 1.

1 marks the furnace chamber, 2 the shell 20 of the furnace, 3 the bottom plate, and 4 the furnace lining. Trunnions 5 are arranged on the shell and these are supported in bearings in the supporting posts 6. A gear 7 is arranged on one of the trunnions. 25 This meshes a gear 8, the gear having the operating handles 9. A locking pawl 10 operates on the gear 8 and is provided with a pedal 11 by means of which the pawl may be withdrawn from the gear to permit the 30 swinging of the furnace. On the release of the pedal the pawl engages the gear 8 in the usual manner. Fuel is delivered to the furnace through one of the trunnions by means of a jet 12 and air is delivered in 35 proper proportion through the pipe 13. The products of combustion pass out through the pipe 14. This pipe extends into a telescoping pipe 15 which may be removed to permit the swinging of the furnace. A supporting 40 block 16 projects upwardly from the bottom of the furnace. It has a hollow metal post 17 extending up through the block. This post is screw threaded and the screw operates in the screw threaded opening 18 45 in the bottom. The projecting block is formed of refractory material around the metal post. A plate 19 preferably of asbestos is arranged on top of the post and a crucible 20 rests on this plate. In use the 50 crucibles are of somewhat varying height and as the top edges disintegrate it is desirable to vary the height of the support. This is accomplished in the present instance by the adjustment of the post 17 by 55 means of the screw thread heretofore described. As the post is raised washer-like

plates 21 are placed over the post so as to build up the block around the post.

In order to maintain the post and supporting block in a cool condition I prefer to deliver air to the metallic portion of the post. This may be done through a flexible tubing 22 which terminates at the bottom of the post 17. The air may be discharged through the openings 23 which are controlled by a 60 shutter valve 24, or, if desired especially if solid fuel is used as a substitute for the liquid fuel through the jet 12 the air may be delivered through radial openings 25 these extending through the metallic post 70 and the refractory material around the post.

The cover 26 is lined with refractory material and has an opening 27. The cover is adapted to make a comparatively close fit with the crucible when the support 17 is 75 properly adjusted. The cover is ordinarily provided with the lips 28 which extend over the eye 29 on the case 2 and the bolts 30 extend through these lips. By removing the bolt at either side the other side may be used 80 as a hinge so as to swing the cover to open position, or both bolts may be removed and the cover lifted as a whole.

The supporting block should be projected 85 sufficiently high to provide a reservoir around its outer surface of sufficient capacity to hold the metal which is melted in the crucible so that if there is an accidental breaking of the crucible this metal may be received by this reservoir and may be poured 90 from the furnace itself so that the heat need not be lost.

By maintaining the crucible support in a cool condition it does not tend to disintegrate 95 as where it is subjected to the intense heat and further there is not the tendency for the metal if there is any dropped into the bottom of the furnace to adhere to the support and this is particularly advantageous with the tilting furnace because the bottom 100 may be entirely closed and still the discharge of the metal from the furnace when it is tilted fairly well assured.

It will be observed that it is possible to utilize the furnace itself as a melting pot. 105 Certain metals may be melted in the furnace in the circular chamber around the supporting block at the same time metal is melted in the crucible. When this is done it is desirable to have the projection high enough 110 to hold not only the metal around the block but also the metal of the crucible so that

if the crucible breaks the metal therein may be contained in the chamber around the support.

What I claim as new is:—

5. 1. In a metal melting furnace, the combination of a tilting metal furnace chamber with a closed bottom; and a crucible support projecting upwardly from the bottom of the furnace a sufficient height to provide a reservoir surrounding the support equal in capacity to a crucible adapted to rest on the support within the furnace and to position the top of the crucible relatively to the top of the furnace to close the crucible. 50
10. 2. In a metal melting furnace, the combination of a tilting metal furnace chamber; a crucible support projecting upwardly from the bottom of the furnace comprising a metal post; and positive means for cooling 60 the post. 15
15. 3. In a metal melting furnace, the combination of a tilting metal furnace chamber; a crucible support projecting upwardly from the bottom of the furnace comprising a hollow metal post; means for cooling the post comprising an air inlet and outlet and means for delivering air to the inlet to effect 70 a circulation through the post. 20
20. 4. In a metal melting furnace, the combination of a tilting metal furnace chamber; a crucible support projecting upwardly from the bottom of the furnace comprising a hollow metal post; and means for cooling the post comprising an air inlet and outlet, the outlet being in the form of twyers leading from the post to the furnace. 75
25. 5. In a metal melting furnace, the combination of a tilting metal furnace chamber; a crucible support projecting upwardly from the bottom of the furnace comprising a metal post; and means for adjusting the height of the post, whereby the crucible carried by the support may be adjusted with 80 relation to the top of the furnace so as to maintain a closure between the furnace proper and the crucible. 45
30. 6. In a metal melting furnace, the combination of a tilting metal furnace chamber; a crucible support projecting upwardly from the bottom of the furnace comprising a metal post; and means for adjusting the post independently of the coating. 55
35. 7. In a metal melting furnace, the combination of a tilting metal furnace chamber; a crucible support projecting upwardly from the bottom of the furnace comprising a metallic post having a refractory coating; 60 and means for adjusting the post independently of the coating. 60
40. 8. In a metal melting furnace, the combination of a tilting metal furnace chamber; a crucible support projecting upwardly from the bottom of the furnace comprising a metallic post having a refractory coating; 65 means for adjusting the post independently of the coating; and means for varying the height of the coating as the metallic post 70 is adjusted. 70
45. 9. In a metal melting furnace, the combination of a tilting metal furnace chamber; a crucible support projecting upwardly from the bottom of the furnace; a cover for 75 the furnace; means for adjusting the support so as to adjust the top of the crucible with relation to the cover to form a closure between the cover and the crucible; means for inducing combustion in the furnace; and 80 a flue extending from the furnace for discharging the products of combustion. 80
50. 10. In a metal melting furnace, the combination of a tilting metal furnace chamber; a crucible support projecting upwardly from 85 the bottom of the furnace; a cover for the furnace; means for adjusting the support so as to adjust the top of the crucible with relation to the cover to form a closure between the cover and the crucible; means for 90 inducing combustion in the furnace; and a flue extending from the furnace for discharging the products of combustion, said flue having a telescopic connection. 90

In testimony whereof I have hereunto set 95 my hand.

GEORGE C. RAHN.
